US00D892120S

(12) **United States Design Patent** (10) Patent No.: **US D892,120 S**
(45) Date of Patent: **** Aug. 4, 2020**

(54) **ADAPTER ASSEMBLY**

(71) Applicant: **Google LLC**, Mountain View, CA (US)

(72) Inventors: **Kenneth Sweet**, San Francisco, CA (US); **Maj Isabelle Olsson**, Sunnyvale, CA (US); **Peter Michael Cazalet**, Los Gatos, CA (US); **Gina Reimann**, Los Gatos, CA (US)

(73) Assignee: **Google LLC**, Mountain View, CA (US)

(**) Term: **15 Years**

(21) Appl. No.: **29/719,720**

(22) Filed: **Jan. 7, 2020**

Related U.S. Application Data

(62) Division of application No. 29/685,699, filed on Mar. 29, 2019, now abandoned, which is a division of application No. 29/612,915, filed on Aug. 4, 2017, now Pat. No. Des. 851,089.

CLAIM

The ornamental design for an adapter assembly, as shown and described.

DESCRIPTION

FIG. 1 is a front perspective view of an adapter assembly according to our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof; and,

FIG. 7 is a bottom elevation view thereof.

Broken lines are environmental only and form no part of the claimed design.

1 Claim, 4 Drawing Sheets
